THERMAL RELAY

Oscar S. Field, Rochester, N. Y., assignor to
General Railway Signal Company, Rochester,
N. Y.

Application June 24, 1936, Serial No. 87,068

5 Claims. (Cl. 200—113)

This invention relates in general to relays, and has more particular reference to a thermal relay with special adjusting means for adjusting for changes of voltage, and for varying the timing of operation of the relay.

Among the objects of the present invention is to provide a thermal relay which can be readily adjusted for changes of voltage, so as to maintain the timing of the relay operation practically constant.

Another object is to provide a thermal relay which can be readily adjusted to give various times of operation.

More specifically, it is proposed in accordance with this invention to provide means whereby the position of a fixed front contact can be adjusted, whereby to vary the requisite amount of travel of a movable contact, and thereby vary the time of operation of the relay.

Further objects, purposes and characteristic features will appear as the description progresses, reference being made to the accompanying drawings showing, solely by way of example, and in no manner in a limiting sense, one form which the invention can assume. In the drawing:

Fig. 1 is an elevational view with parts shown in section.

Fig. 2 is a sectional view on line 2—2 of Fig. 1, viewed in the direction of the arrows.

The relay of this invention is of the same general type as shown in Patent 1,902,793, patented March 21, 1933, to J. E. Willing, and in general involves a compensated bi-metallic thermal element carrying movable contacts which operate between a fixed back contact and a fixed front contact, and measure a time interval during its travel from the fixed back contact to the fixed front contact and back again to the fixed back contact.

Referring now to the drawing, the device includes a housing 1, having a top plate 2, in which is a groove 3, for receiving the upper ends of rigid brackets 4 and 5, respectively carrying a fixed back contact 6, and a fixed front contact 7.

The brackets 4 and 5 are clamped in position by means of binding posts 8 and 10. It can be seen from the sectioned portion of the post 10, that its threaded stem is passed up through the top plate to bring a fixed head 11 in position to clamp bracket 5 against the top plate as a tightening nut 12 is screwed down against the top face of the top plate. The other bracket 4 is attached to the top plate in the same manner as just described.

The movable contact member 12 is compen-

sated for ambient temperature changes, but this need not be described herein since it constitutes no part of the present invention. This movable contact number 12 is carried by the top plate, by binding post 9 in the manner described above, and has a heating element 13 which, when energized, causes the movable contact member 12 to move to the left and make contact with fixed contact 7, and when de-energized to return to its shown position, where it makes contact with fixed contact 6.

Referring now more particularly to the binding post 10, it is seen that this post is hollow, and receives a stem 14, having a head 15 thereon which bears against the head 11 of the post, to thereby limit the upward movement of stem 14. On the outer end of stem 14 is a thumb nut 16, pinned thereto, and this thumb nut 16 is furnished with a seal 17, whereby to attach it to a plate 18, keyed to the post 10, whereby to prevent turning of the thumb nut 16 when the seal is in place, there being a plurality of apertures in the plate 18 for variously receiving the seal.

Carried by the inner end 19 of stem 14, which inner end is threaded, is a rectangular box-like traveler 20, received on this threaded end, and restrained from rotation therewith by the bracket 5, which is received between the two arms 21 of member 20. Also carried by the two arms 21 is a roller member 22, which bears against the spring carrying member 23 of fixed contact 7, this member 23 being formed, as shown in Fig. 1, to be inclined inwardly toward the lower end of threaded stem 19.

With this arrangement of parts, it can be seen that rotation of thumb nut 16, causes the threaded stem 19 to rotate, to thereby cause traveler 20 to move along the stem so that roller 22 bears against, and results in movement of, fixed contact 7 either to the right or the left, according as the traveler moves downwardly or upwardly.

Should there be no safeguard against improper adjustment of the contacts, it would be possible to move fixed contact 7 so as to make contact with movable contact member 12, with the relay de-energized, and thereby defeat the time measuring function of the relay. To avoid any such misuse of the adjusting means, a stop nut 24 is positioned on threaded stem 19, and locked in position, as by a set screw 25, in such a position as to limit the traveler 20 to a travel just insufficient to cause fixed contact 7 to make contact with movable contact member 12 when the relay is de-energized.

With the above structure it is clear that, should

it be desired to maintain the operating time of the relay constant, even though there be variations in the voltage applied to the heating winding 13, this can be accomplished by adjusting the position of the fixed contact 7 with respect to the movable contact member 12.

Furthermore, in various situations, it is desirable to cause the relay to measure various different elapsed time periods and here again and 10 adjusting means of this invention permits ready and accurate adjustment of the position of the front fixed contact, to thereby vary the time, as desired, and within the limitation of the structure involved.

15 It can be seen that, with the threaded stem 19, causing the traveler 20 to move, very minute and accurate movements of the traveler can be obtained, and the traveler can be held accurately in adjusted position without any danger of disturbing the desired position thereof, while fixing this adjustment by means of seal 17. This threaded traveler member is thus much more desirable for effecting adjustments than other mechanical means which would lend themselves 20 less readily to accurate minute adjustments and desired fixing of the adjustment after it is obtained.

The above rather specific description of one form of the present invention is given solely by 25 way of illustration, and is not intended, in any manner whatsoever, in a limiting sense. Obviously the invention can assume various physical forms, and is susceptible of numerous modifications, and all such forms and modifications are 30 intended to be included in this application, as come within the scope of the appended claims.

Having described my invention, I now claim:—

1. In a thermal relay, in combination, a casing, a top plate on the casing, a movable contact 40 carried by the top plate, a hollow post on the top plate, a rigid support bracket clamped between the post and the plate, a front contact spaced from the movable contact, a stem passing through the hollow post, a thumb nut on the outer end 45 of the stem, a threaded inner end on the stem, a spring arm connecting the front contact to the bracket and spaced from the threaded inner end, a threaded traveller on the inner end of the stem, a bifurcation in the traveller receiving the bracket, and cam means on the traveller bearing 50 against the spring arm to vary the position of the front contact.

2. In a thermal relay, in combination, a casing, a top plate on the casing, a movable contact carried by the top plate, a hollow post on the top 55 plate, a rigid support bracket clamped between the post and the plate, a front contact spaced from the movable contact, a stem passing through the hollow post, a thumb nut on the outer end of the stem, a threaded inner end on the stem and extending parallel to, and spaced from, the bracket, a spring arm connecting the front contact to the bracket and spaced from the bracket,

a threaded traveller on the inner end of the stem, a bifurcation in the traveller receiving the bracket, cam means on the traveller bearing against the spring arm to vary the position of the front contact upon movement of the traveller, and a 5 stop member fixed to the threaded end of the stem and so positioned as to prevent the traveller from causing the front contact to touch the movable contact.

3. In a thermal relay, in combination, a movable contact, a fixed contact spaced therefrom, a spring arm carrying the fixed contact, a rigid bracket spaced from, and inclined to, the major part of the spring arm and carrying the same, a threaded stem spaced from, and substantially 10 parallel to, the bracket, means for turning the stem, a bifurcated nut on the stem, the bracket being received in the bifurcation of the nut for preventing rotation of the nut with the stem, and a roller carried by the nut and bearing against the spring arm, whereby to cause the nut to travel on the stem when the stem is turned and the roller to move the fixed contact.

4. In a thermal relay, in combination, a movable contact, a fixed contact spaced therefrom, a spring arm carrying the fixed contact, a rigid bracket spaced from the major part of the spring arm and carrying the same, a threaded stem spaced from, and substantially parallel to, the bracket, means for turning the stem, a bifurcated 25 nut on the stem, the bracket being received in the bifurcation of the nut and preventing rotation of the nut with the stem, and a roller carried by the nut and bearing against the spring arm, whereby to cause the nut to travel on the 30 stem when the stem is turned and the roller to move the fixed contact, said spring arm being inclined toward the bracket so as to cause the roller to always bear thereagainst and produce a camming action on the spring arm and fixed 35 contact upon movement of the nut.

5. In a thermal relay, in combination, a movable contact, a fixed contact spaced therefrom, a spring arm carrying the fixed contact, a rigid bracket spaced from part of the spring arm and 45 carrying the same, a threaded stem spaced from, and substantially parallel to, the bracket, means for turning the stem, a bifurcated nut on the stem, the bracket being received in the bifurcation of the nut and preventing rotation of the 50 nut with the stem, a roller carried by the nut and bearing against the spring arms whereby to cause the nut to travel on the stem, when the stem is turned, and the roller to move the fixed contact, the spring arm being inclined toward the bracket to cause the roller to always bear thereagainst and produce a camming action on the 55 spring arm and fixed contact, and a fixed stop member on the threaded stem positioned to stop travel of the nut before the contacts touch each other.

OSCAR S. FIELD.
